Filed Nov. 25, 1968, Ser. No. 14,648

Term of patent 14 years

Int. Cl. D8—02

U.S. Cl. D8—70

FIG. 1

FIG. 6

FIG. 7

FIG. 1 is a front view of a saber saw blade showing my new design;

FIG. 2 is a left side view of FIG. 1;

FIG. 3 is a right side view of FIG. 1;

FIG. 4 is a top view of FIG. 1;

FIG. 5 is a bottom view of FIG. 1;

FIG. 6 is a front view of a saber saw blade showing another embodiment of my new design; and

FIG. 7 is a front view of a saber saw blade showing another embodiment of my new design.

Portions of the design of FIG. 6 have been broken away to indicate indeterminate length and portions have been omitted from FIG. 7 for convenience of illustration.

The characteristic features of my design reside in the curved gullet connecting the shank and cutting portions

of the blade together with the offset of both the toothed and back edges of the cutting portion relative to the corresponding edges of the shank portions.

I claim:

The ornamental design of a scroll saber saw blade, as shown and described.
